UNITED STATES PATENT OFFICE.

ANDREW D. ARMSTRONG, OF CHICAGO, ILLINOIS.

DESIGN FOR A LEVEL.

42,347.

Specification for Design. Patented Mar. 26, 1912.

Application filed April 21, 1911. Serial No. 622,631. Term of patent 7 years.

To all whom it may concern:

Be it known that I, ANDREW D. ARMSTRONG, a citizen of the United States, and a resident of the city of Chicago, county of Cook, and State of Illinois, have invented a new, original, and ornamental Design for Levels, of which the following is a specification, reference being had to the accompanying drawing, forming a part thereof.

The figure is a plan view of a level showing my new design.

I claim:

The ornamental design for a level as shown.

In testimony whereof I have signed my name to this specification in the presence of two subscribing witnesses.

ANDREW D. ARMSTRONG.
